(57) **CLAIM**We claim the ornamental design for a set of engine valve
covers, as shown and described.

DESCRIPTION

FIG. 1 is a front perspective view of a driver side engine
valve cover showing our new design.

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front perspective view of a passenger side engine
valve cover showing our new design.

FIG. 9 is a front elevational view thereof;

FIG. 10 is a back elevational view thereof;

FIG. 11 is a left side elevational view thereof;

FIG. 12 is a right side elevational view thereof;

FIG. 13 is a top plan view thereof; and,

FIG. 14 is a bottom plan view thereof.

The broken lines disclosure represents unclaimed portions of
the valve covers in which the design is embodied.**1 Claim, 8 Drawing Sheets**| (56) References Cited
